DOOR SUPPORTING AND GUIDING MEANS

Kenneth J. Tobin, Chicago, Ill., assignor, by
mesne assignments, to The Youngstown Steel
Door Company, Cleveland, Ohio, a corporation
of Ohio

Application January 18, 1932, Serial No. 587,173

5 Claims. (Cl. 189—46)

This invention relates to car doors and concerns itself more particularly with the supporting and guiding means for said doors and the arrangement of the doors upon the car.

5 The invention comprises the novel structure and combination of parts hereinafter described and more particularly pointed out and defined in the appended claims.

In the drawings

10 Figure 1 is a fragmentary elevation of a freight house car showing one embodiment of the invention applied thereto.

Figure 2 is a sectional view taken on line 2—2 of Figure 1.

15 Figure 3 is a sectional view taken on line 3—3 of Figure 1.

Figure 4 is a sectional view similar to Figure 3 showing the relationship of the parts of the door supporting means in the elevated position of the door.

20 Figure 5 is a partial sectional view similar to Figure 2, showing a modified form of the invention.

Figure 6 is a partial sectional view similar to 25 Figure 3, illustrating the operating mechanism employed with the form of invention shown in Figure 5.

Figure 7 is a partial sectional view similar to 30 Figure 3, showing a further modification of the invention.

Figure 8 is a view similar to Figure 3, showing the operating mechanism applied to the door illustrated in Figure 7.

35 Figure 9 is a sectional view taken on line 9—9 of Figure 1.

Figure 10 is a partial elevational detail showing the attachment of the runway actuating bracket to the runway.

Referring to the embodiment of the invention 40 illustrated in Figures 1 to 4, inclusive, there is illustrated fragmentarily a railway house car 10 embodying in its construction a side plate 11 and a side sill 12.

45 As clearly indicated in Figure 2 of the drawings the side plate 11 is positioned so that one of its flanges 13 extends downwardly from the web 14 thereof and lies in a substantially vertical plane. To the flange 13 there is secured a number of braces 15, one of which is illustrated in Figure 2 of the drawings. The vertical flange 13 also has secured thereto the metallic sheathing 16 of the car. The side plate 11 carries a header member 17 and a retaining member 18 by secure- 50 ment through the rivets 19 to the flange 13 of the side plate. The header 17 extends between door posts, one of which is illustrated at 20, these posts

defining the longitudinal extent of a door opening formed in the side of the car. The horizontal flange 21 of the header member is sheared so that it does not extend beyond the door posts. The retaining member 18, which preferably takes the form of a Z-bar, is positioned with one of its flanges 22 extending downwardly and its web 23 extending horizontally in spaced relation to the horizontal flange 21 of the header member. The relationship between the header and retaining members provides a compartment adapted to receive the upper margin of the door 24 and provides a weatherproofing assembly with said upper margin of the door. To further increase the weatherproofing qualities at this margin of the door an angle member 25 is secured thereto. In addition to the function of the retaining member as weatherproofing means it will be apparent that said member, as shown in Figure 1 of the drawings, is of such extent as to prevent the upper margin of the door from falling outwardly away from the car.

The side sill 12 preferably takes the form of an angle member having a substantially vertical upstanding flange 26 and a horizontal inwardly extending flange 27. That portion of the flange 26 of the sill 12 which lies within the door opening is cut away as indicated at 28 and a portion of the remainder of said vertical flange positioned within the opening is preferably bent downwardly and outwardly to provide a horizontal supporting flange 29. The lower portions of the bracing members 15 and the sheathing 16 are riveted or otherwise suitably secured to the upstanding flange 26 of the sill. Lying within the door opening and upon the floor 30 of a car is a threshold plate 31 supported beyond the floor by means of the flange 29 formed on the side sill. At its outer end the threshold plate 31 is turned downwardly to provide a flange 32 which, as illustrated in Figure 2 of the drawings, may if desired be bent inwardly.

In order to support the door 24 utilized to close the opening in the car side for movement relative to said opening an angular member 33 is employed. This member preferably takes the form of a Z-bar positioned with one of its flanges 34 extending inwardly relative to the car in abutting relationship to the flange 27 of the side sill to which flange it may be secured. The flange 35 of the angular member extends vertically and downwardly from the flange 34 and from the lower margin of the flange 35 a horizontal flange 36 extends outwardly and forms a track upon which the door 24 is supported. It is to be ob- 55

served that the angular member 33 may extend for a distance equal substantially to the length of travel of the door or, if preferred, it may extend the entire length of the side sill 12. It is 5 to be noted, furthermore that the angular member 33 compensates for the cut-away portion of the sill between the door posts.

A plurality of brackets 37 and 38 are secured to the lower corners of the door 24. These 10 brackets extend downwardly from the lower margin of the door and with the lift door with which the invention is illustrated this extent is such as to insure frictional engagement between said brackets and the track flange 36 of the angular member 33 in the lowered position of the door. Each of the brackets is provided with an up- 15 standing leg 39 spaced from the bracket and lying in overlapping relationship with the downwardly extending flange 32 provided on the threshold plate. By this construction it is clear that in the movement of the door longitudinally of the car it will be guided by the flanges 32 and 38 and that said flanges cooperate to prevent excessive outward movement of the door relative 20 to the car. As heretofore noted the threshold plate 31 lies in the door opening only and, consequently, the flange 32 is effective for its purpose only within the door opening. To maintain 25 the guiding and retaining arrangement beyond the door opening an angular member 40 secured to the side sill is employed. The member 40, as shown in Figure 2 of the drawings, is positioned relative to the threshold plate 31 in such manner 30 that the horizontal leg 41 of the member 40 is in alignment with the threshold plate and the downwardly and inwardly extending leg 42 of the member 40 is in alignment with the flange 32 provided 35 on the threshold plate.

The mechanism for elevating the door and for 40 supporting said door for movement upon the track flange 36 embodies a runway 43, each end of which is closed by means of a member 44 carrying an eccentrically positioned trunnion 45. These trunnions are journaled in their respective 45 bracket members as indicated at 46. The runway 43, as clearly illustrated in Figure 2 of the drawings, is provided with diverging legs 47 and 48 between which bearing balls 49 are adapted to be received in abutting relationship with shoulders 50 and 51 formed on the legs of the runway. A spacer 52 is utilized to maintain the bearing balls 55 in the desired spaced relationship. Extending between the brackets 37 and 38 is a plate member 53, the upper margin of which is secured to the lower margin of the door and the ends of which are secured to said brackets. This plate member, as clearly shown in Figure 2 of the drawings, is positioned outwardly of the runway 43 so as to 60 protect it from the elements. It is to be observed, furthermore, from this figure of the drawings that the lower end of the plate member 53 lies in proximity to the outer margin of the track flange 36 in the lowered position of the door. Furthermore, the threshold plate lies in 65 proximity to the adjacent portion of said door. By this relationship it becomes apparent that not only is the runway protected from the weather but that entry of the elements into the car from below the door is obviated.

70 Mechanism is provided to elevate the door so that the frictional engagement between the brackets and the track flanges 36 is broken and the door is supported upon the bearing balls for desired movement. This mechanism comprises 75 an operating lever 54 pivotally supported upon a

boss 55 carried by a bracket member 56 secured substantially centrally of the door. The operating lever 54 is provided with an opening 57 through which is adapted to extend one end of a link 58. The other end of the link 58 is connected to an actuating arm 59 provided on a bracket member 60 lying within and secured to the runway 43. The actuating arm 59 extends through an opening 61 formed in the runway and through an opening 62 formed in the plate member 53 in 10 order to permit its connection with the link 58. The connection between said bracket member and the runway is illustrated in greater detail in Figure 10 of the drawings. The bracket member 60 adjacent the inner leg 47 of the runway is provided with a curved flange 63 extending through an opening 64 formed in said leg. The curved flange 63 of the bracket member lies within a correspondingly curved flange 65 formed on the bracket 56 secured to the door. This bracket 56 is offset as indicated at 66 to permit assembly 15 between the curved flanges 63 and 64.

Figures 5 and 6, illustrate a modified form of the invention. In this form of the invention the plate member 53 is dispensed with. The runway 25 67 is pivoted eccentrically as hereinabove set forth to bracket members secured to the lower margins of the doors, one of said bracket members being designated 68. Moreover, the substantially centrally positioned bracket 69 upon which the operating lever 70 is fulcrumed is provided with an upstanding flange 71 cooperating with the downturned flange 73 of the threshold plate 74 to guide and retain the lower margin of the door. A slightly modified form of link 75 is utilized in 30 the lifting mechanism for the door and a bracket 76 secured to the outside of the runway 67 is utilized in place of the arm 59 shown in Figure 3 of the drawings. The center bearing arrangement is maintained. It is to be noted that a separate angle member 77 secured to the vertical flange of the side sill 12 is employed in place of 35 the integral outwardly bent flange 28.

The modified form of the invention illustrated in Figures 7 and 8 utilizes a plate member 78 45 which, however, extends inwardly from the lower margin of the door to which it is secured. It is to be noted, however, that the weatherproofing features afforded by this plate are not vitiated by this arrangement. The elevating mechanism 50 utilized in this form of the invention is substantially the same as that illustrated in Figure 6 of the drawings. The guiding and retaining flange 79 and the curved flange 80 are in this form of the invention provided by separate members secured 55 to the plate member 78.

The mode of operation of the door in each of the embodiments of the invention illustrated is the same. It will be apparent that when a downward pull is exerted upon the free end of the operating lever 54 a force will be transmitted through the link 58 or 75, imparting transverse movement to the runway about the bearing balls as fulcrums and effecting a lifting of the door by means of the eccentric pivotal engagement between said runway and the brackets rigidly secured to the door. The door may then be moved in the desired direction upon the balls which now support the weight thereof upon the track flange. 70

It is apparent that numerous changes and modifications in the structure of the embodiment shown will occur to those skilled in the art and it is intended, consequently, to include all such changes and modifications within this invention. 75

which is to be limited only by the scope of the claims appended hereto.

I claim:

1. In a house car having a door opening, in combination, a side sill, an outwardly directed flange carried by said sill and forming a track, a threshold member lying in said door opening and having a depending flange positioned above said track, said side sill having a horizontal flange adapted to provide a support for said threshold member.

2. In a house car having a door opening, in combination, a side sill, an outwardly directed flange carried by said sill and forming a track, a threshold member lying in said door opening and having a depending flange positioned above said track, means carried by said car beyond said door opening having a depending flange aligned with the depending flange of said threshold member, a door supported upon said track for sliding movement, bracket members secured to the lower corners of said door and flanges carried by said brackets in overlapping relationship with said depending flanges for the purpose set forth.

3. In a house car having a door opening, a longitudinally extending member, a bar secured to said member with its web depending vertically from said member and one flange extending outwardly, a threshold plate lying in said door opening and having a downwardly projecting flange spaced from said outwardly extending flange, a

door supported upon said latter flange for sliding movement, and spaced flanges carried by said door adjacent the lower corners thereof adapted to overlap said downwardly projecting flange for the purpose set forth.

4. In a house car, in combination, a side sill, an outwardly directed flange carried by said sill and forming a track, a door, brackets secured to the lower corners of said door and extending downwardly therefrom, a plate member secured between said brackets to the lower margin of said door and extending downwardly in proximate relation to the track, said plate member and said brackets providing a pocket and means positioned in said pocket and lying between said brackets adapted to support said door for sliding movement upon the track.

5. In a house car having a door opening, in combination, a side sill, an outwardly directed flange carried by said sill and forming a track, a threshold member lying in said door opening and having a depending flange positioned above said track, means carried by said car beyond said door opening having a depending flange aligned with the depending flange of said threshold member, a door supported upon said track for sliding movement, and means carried by said door for interlocking relationship with said depending flanges for the purpose set forth.

KENNETH J. TOBIN.
